UNITED STATES PATENT OFFICE.

EDWIN T. BASKIN, OF INDEPENDENCE, MISSOURI.

GLOVE.

1,209,380.

Specification of Letters Patent. Patented Dec. 19, 1916.

Application filed September 3, 1915. Serial No. 48,906.

To all whom it may concern:

Be it known that I, EDWIN T. BASKIN, a citizen of the United States, residing at Independence, in the county of Jackson and State 5 of Missouri, have invented certain new and useful Improvements in Gloves; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 My invention relates to hand coverings and more particularly to a glove or mitten of the reversible type, that is, one wherein the thumb is arranged centrally at one edge of the glove or mitten so that the latter is 20 adapted for use on either hand and may be reversed to wear the same equally at each side, and thereby lengthen the life of the hand covering.

It is the principal object of the present invention to provide a hand covering of this 25 character with thumb and body reinforcement that is taken from the material of which the thumb and body blanks are formed, to provide the reinforcement without waste of material, and, also, to provide 30 an improved finger piece for insertion in the body blank without unduly spreading the finger members while securing the proper width for the glove or mitten. In accomplishing these objects I have provided improved details of structure, the preferred 35 forms of which are illustrated in the accompanying drawing, wherein:—

Figure I is a plan view of a blank for 40 forming a glove in accordance with my invention, the reinforcement being cut in the blank but not entirely severed therefrom. Fig. II is a similar view of the thumb blank. Fig. III is a plan view of the body blank of 45 a glove, indicating the reinforcement folded onto the blank and the mode of applying the inserted finger members to the blank to complete the glove. Fig. IV is a similar view after the thumb blank has been applied 50 to the body blank and showing the inserted finger members partially assembled. Figs. V and VI are detail views of the inserted finger blanks. Fig. VII is a detail view of a 55 glove containing my improvements, showing the glove as it appears when turned inside out. Fig. VIII is a similar view of the

glove under normal conditions. Fig. IX is a plan view of a mitten blank, illustrating the application of my improvements thereto, the thumb blank being shown in dotted lines 60 in its relation to the body blank. Fig. X is a detail view of a completed mitten, the reinforcing members being shown in dotted lines.

Referring more in detail to the drawings: 1 designates a blank, cut to form a reversible 65 glove and comprising a palm portion 2, first, third and fourth finger sections 3, 4 and 5, and thumb recess 6; the material that is cut from the body blank to form the recess 6 being connected to the said blank by a neck 70 7, instead of entirely severed therefrom, so that an ear 8 that is formed when the recess is cut retains its connection with the body blank and can be folded back thereover (Fig. 3) to form a reinforcement along the edge 75 of the glove at a point where the greatest wear is encountered.

10 designates a thumb blank which may be properly shaped to form a thumb pocket when folded upon itself and stitched along 80 the edges of the blank, and cut from the thumb blank, at the base end thereof, is an ear 11, for forming the thumb recess 12, which, in combination with the recess 6 in the body member, forms an opening through 85 which a wearer's thumb may be projected. As in the case of the body blank, the ear 11 retains its connection with blank 10 through a neck 13, so that when the ear 11 is turned back over the body of the blank, and, if so 90 desired, stitched along its edges to the blank, it also forms a reinforcement along the inner edge of the thumb piece, so that an article held between the thumb and palm portion of the hand wears against the reinforced thumb 95 and body portions of the glove.

It will be noted in Figs. I, III and IV that the body blank 1 has no second finger section cut therefrom. This formation is for the reason that it is necessary to spread the 100 blank at the finger position in order to accommodate the increased width of the hand at this point, this increase in width being secured by inserting one of the finger sections, usually the second finger section. In the present embodiment of my invention however, I provide an improved construction of insert finger blanks which, when combined with the body blank, form a smooth and effective insert section, the 105 blanks being termed front and back blanks although they may be reversible.

To clearly describe the structure I designate the front blank by the numeral 15, and the back blank by the numeral 16, the front blank 15 being shaped to comprise a pointed inner end, the point being at the center of the blank and the inclined edges corresponding in outline so that the point may be arranged at the center of the crotch between the finger sections in the body blank when the parts are assembled. The back blank 16 is the reverse of that designated the front blank in that instead of having the point 18 it has a recess 19, the recess or notch terminating in a point at the center of the blank and having a depth substantially equal to the projection of the point 18 of the front blank 15.

In the manufacture and assemblage of a glove of this description the body and thumb blanks are cut as described, with the reinforcing ears connected with the blanks by the necks as heretofore mentioned. After the blanks are cut the first operation is to turn the reinforcing ears back onto the blanks and sew the same thereto, the sewing being accomplished along the edges of the ears opposite the neck and, if desired, along the side edges as well, although the latter is not essential. After the reinforcing ears have been attached to their blanks the inserted finger members are installed by laying one of the inclined edges of the front blank along one of the edges of the first or third finger blanks and sewing the parts together, the opposite inclined edge of the blank being then sewed to the edge of the adjacent finger section to complete the installation of the finger blank. After the first blank has been installed, as described, the opposite blank is applied to the opposite half of the body blank, between relative finger sections, in the same manner as described with reference to the first inserted finger blanks, the only difference being that instead of the projecting points terminating at the base of the crotch between the finger sections, the point of the notch in the section 16 will lie over the base of the crotch. After the insert finger sections have been applied to the body blank the thumb blank is then applied to the body blank so that the recesses 6 and 12 will overlie each other and the thumb blank sewed to the body blank along the edge of such recesses. The next step in assembling the glove is to fold the body blank along a line extending from the center of the thumb recess so that the finger sections on opposite sides of the blank will overlie each other. The finger sections are then sewed together along their edges to form the finger pockets and the thumb blank is then folded upon

itself and its edges stitched to complete the thumb pocket. An ordinary wrist band then may be applied to the edge of the palm portions in order to complete the glove.

It is apparent that this construction forms a convenient, economical and substantial structure and that the glove is reinforced at the points that receive the hardest wear, the increased wear in the palm of the glove being offset by the adaptability of the glove for reversal, so that both faces of the palm portion may receive an equal amount of wear.

Having thus described my invention, what I claim as new therein and desire to secure by Letters-Patent, is:—

1. A hand covering comprising body and thumb blanks, each provided with slits defining ears and thumb recesses, said ears being connected to their body blanks at the inner edges of the recesses, and turned back upon such blanks and attached thereto to form reinforcing members in the completed article.

2. In a glove, a body blank comprising integral finger sections and independent finger sections, one of the independent sections having an incised V-shaped end with the point of the incision at the base of the crotch between adjacent integral finger sections of the body blank, and the sides of the incised end stitched to the edges of the adjacent finger blanks, whereby the independent finger section is centered relative to the integral finger sections, substantially as set forth.

3. In a glove, a body blank comprising integral finger sections and independent finger sections, one of the independent finger sections having an incised V-shaped end, with the point of the incision located at the base of the crotch between integral finger sections, and the sides of said incised end being attached to the edges of adjacent integral finger sections, the opposite independent finger section having a protruding V-shaped end, with the point of said end located at the base of the crotch between the said adjacent finger sections, and the sides of said end fixed to the sides of the said adjacent sections, the edges of said independent finger sections being stitched together to form a finger member, the V-shaped ends of the independent finger sections effecting the centering or placement of said independent sections between the adjacent integral finger sections, substantially as set forth.

In testimony whereof I affix my signature.

EDWIN T. BASKIN.
